AUTOMATIC OVERHEAD DOOR

Karl E. Johanson, Oak Lawn, Ill.

Application March 22, 1946, Serial No. 656,494

6 Claims. (Cl. 268—59)

1

This invention relates to power-operated doors for garages, factories, warehouses, and the like.

The main objects of this invention are to provide power-operated door structures having improved means for mounting the doors for shifting between closed and open positions; to provide improved counterbalancing means for such a door so that a minimum amount of power or force is required to shift the door between its open and closed positions; to provide improved draft means for causing the shifting of the door between its open and closed positions; to provide improved clutch mechanism for connecting said draft means with a source of power; to provide improved means for controlling the operation of said clutch means; to provide improved brake means synchronized with the shifting of said clutch mechanism to check and restrain the action of said draft means when said clutch mechanism is retracted; and to provide improved means for automatically checking the movement of the door toward a closed position when it strikes an obstruction or reaches the limit of its travel to its fully closed position.

Alternate forms of draft means for power-operated doors and various modifications of clutch mechanism for connecting such means to different types of motor suitable for opening and closing doors are shown in the accompanying drawings, in which:

Fig. 1 is a vertical sectional elevation showing the improved door construction and mounting means for power-operated doors of this kind;

Fig. 2 is an enlarged transverse, vertical, sectional detail taken on the line 2—2 of Fig. 1;

Fig. 3 is a cross-sectional detail taken on the line 3—3 of Fig. 2;

Fig. 4 is a partly sectional and partly elevational detail taken on the line 4—4 of Fig. 2, showing the preferred form of draft means by which the door is shifted between its open and closed positions;

Fig. 5 is a cross-sectional detail view taken on the line 5—5 of Fig. 2;

Fig. 6 is an enlarged horizontal sectional detail view taken on the line 6—6 of Fig. 1 of one form of an interrelated clutch and brake mechanism for controlling the operative functioning of draft means through which the power of a unidirectional motor is transmitted for the opposite shifting of the door between its closed and open positions;

Fig. 7 is a side elevational view, partly sectional and partly broken away, of a modified form of draft means whereby the motor is connected to shift the door;

Fig. 8 is a longitudinal sectional view of the construction shown in Fig. 7, taken on the line 8—8;

Fig. 9 is a detail view, taken on the line 9—9 of

2

Fig. 8, showing the belt-controlled "overload" means whereby an "overload" switch is actuated to arrest further movement of the door, when its closing movement is checked by some obstruction in the doorway;

Fig. 10 is a diagrammatic view of the electrical circuit and switch mechanisms for controlling the operation of the clutch and brake mechanism shown in Fig. 6, and Figs. 7 and 8;

Fig. 11 is a sectional elevation of an adaptation of the clutch and brake mechanism, shown in Fig. 6, for use with a reversible motor;

Fig. 12 is a transverse sectional view, partly broken away, taken on the line 12—12 of Fig. 11;

Fig. 13 is a sectional view taken on the line 13—13 of Fig. 11.

Fig. 14 is a partly sectional and partly elevational detail of a modified form of an interrelated clutch and brake mechanism for controlling the operative functioning of the draft means through which the power of a unidirectional motor is transmitted for the opposite shifting of the door between its closed and open positions;

Fig. 15 is an adaptation of the clutch and brake mechanism, shown in Fig. 14, for use with a reversible motor; and

Fig. 16 is a diagrammatic view of the electrical circuit and switch mechanisms for controlling the operation of the clutch and brake mechanism shown in Fig. 14.

The improved door and power-operated draft mechanism therefor, shown in the accompanying drawings, comprises a door 20 equipped with a counterbalancing means 21 and arranged to be shifted between a vertically-disposed closed position and a horizontally-disposed overhead open position through the action of either a worm-type draft means 22 or a chain-and-sprocket draft means 23 adapted to be connected, through the medium of either an electrically-controlled mechanically-operated clutch and brake mechanism 24 or an electrically-controlled magnetically-operated clutch and brake mechanism 25, to a motor 26.

The door 20, which is of the sectional type, is suspended on transmission means 27 for movement along channel-shaped supports 28 under the action of either type of draft means 22 or 23. Each of the door sections, below the upper section, is equipped with casters 29 operating in the vertical and overhead trackage 30 as the door moves between its closed and open positions, as shown in full and dotted outlines in Fig. 1.

The door transmission means 27 comprises a pinion and roller combination 31 secured at each end of a shaft 32 journaled in brackets 33 secured to the upper corners of the upper section of the door 20. The pinion-roller combination 31 is formed by mounting a pinion 34 between a flange 35 formed on the collar 36 and a ring 37

which is secured to the flange 35, with the pinion in between, by means of pins 38. The collar 36 is keyed to the shaft 32 by means of a pin 39. The flange 35 and ring 37 thus serve as rollers adapted to travel on rails 40, a pair of which are clamped to each of the channel-shaped supports 28 with a rack 41 in between. By virtue of this arrangement the weight of the door, in its closed position, is suspended by the rollers on the rails 40. As the pinions 34 are caused to travel along the racks 41 the door is shifted between its closed and open positions.

The channel-shaped supports 28, by means of suitable brackets, are mounted horizontally along the ceiling from the door opening to a point slightly beyond the extreme travel of the door 20, in its horizontally-disposed open position.

The counterbalance 21 is in the form of a pair of drums 42 each mounted on roller bearings 43 supported on a tubular member 44. Each tubular member 44 is rotatably supported in a pair of L-shaped brackets 45 which are suspended from one of the respective ends of the channel-shaped supports 28, at their forward ends adjacent the door opening. Cables 46, connected at 47 to the lower corners of the bottom door section and at 48 (see Fig. 2) to the drums 42, are adapted to wrap around the respective peripheries of the drums as shown in Fig. 2. In each drum a flat clock spring 49, of conventional form, has the inner end hooked as shown at 50 (see Fig. 5) and slipped through a slot 51 in hub member 44. The other end of the spring is fastened to the drum 42 as shown at 52. A pin 53, inserted through a flanged plate 54 on one of the brackets 45 and through registering apertures 55 in the hub member 44, permits the initial tensioning of the spring 49 so as to secure the proper counterbalancing of the door 20.

The worm type of draft means 22 is the preferred form. This comprises a shaft 56 extending parallel to and along one of the channel-shaped supports 28 and has a spiral thread 57 formed thereon which meshes with a toothed follower 58, connected to the shaft 32. The spirally-threaded shaft 56 is supported throughout its length in a tubular sheath 59 which lies on the bottom of one of the channel-shaped supports 28, inwardly of the combination rail 40 and rack 41, and extends the full length of said support between the front wall of the doorway and the motor-and-clutch-mechanism housing 60. This sheath 59 is open along the upper part thereof to receive and guide the follower 58, as is most clearly shown in Fig. 2.

The spiral thread 57, on the shaft 56, terminates just short of the motor-and-clutch-mechanism housing 60. However, the shaft extends on through the housing and has the rear end thereof supported in a bearing 61 set into the rear wall of said housing 60. Intermediate the ends of the housing 60, a sleeve 62 is secured to the shaft 56 by means of pins 63.

The sleeve 62 affords support for a tube 64, the inner or forward end of which is journaled on a bearing 65 secured to the forward end wall of the housing 60. The opposite or rear end of the tube 64 is internally recessed to receive a head 66, integral on the end of the sleeve 62, and exteriorly threaded to receive a cap 67 which is thereby shiftable along the tube 64 so as to adjust the tension of a spring 68, interposed between the cap end and the sleeve head 66 which yieldingly holds the shaft 56 against axial movement for a purpose that presently will appear more

fully. In order that the tube 64 may rotate with the shaft 56, but permit it to have relative axial movement, the tube 64 is slotted at 69 to receive rollers 70 supported on a pin 71 extending through the shaft 56 and the sleeve 62.

A hand wheel 72, secured to the outer end of the shaft 56, permits turning thereof in emergent situations, to move the door when, for some reason, the electric service is temporarily interrupted.

The follower or carriage 58 has rollers 73 journaled thereon to bear against the under surface of the upper horizontal flange of the channel-shaped support 28. As the shaft 56 is rotated the spiral thread 57 meshing with the row of teeth 74 formed on the underside of the follower 58 moves the follower axially of the shaft 56. Thereupon, the pinions 34, of the pinion-roller combinations 31, travel along the rack 41 and cause a movement of the door 20 between its open and closed positions.

The chain-and-sprocket draft means 23 comprises a pair of sprockets 75 and 76 journaled on one of the channel-shaped supports 28, adjacent opposite ends thereof, and connected by a chain 77. The sprocket 75 is driven by means of a belt and pulley combination 78 whereas the sprocket 76 positions the chain 77 for its connection to a follower 58' by means of a crank 79.

The belt-pulley combination 78 includes grooved pulleys 80 and 81 connected by a V belt 82. The pulley 80 is connected to the sprocket 75 by means of a shaft 83. The pulley 81 is mounted on a shaft 84 which is driven by a motor 26 through the medium of the clutch mechanism 24, as will appear more fully hereinafter.

The crank 79, by which the chain 77 is connected to the follower 58', is pivoted at 85 to one of the links in the sprocket chain 77 and at 86 to a block 87 slidably mounted on the follower 58'. The block 87 has a stem 88 extending through the rear part of the follower 58' and between the rear end of which and a flanged nut 89 on said stem a spring 90 is arranged. This spring normally urges the block 87 rearwardly on the follower 58' but permits it to shift forwardly thereof when the pivotal connection 85 of the crank 79 is moving around the sprocket 76, as is indicated by dotted outlines in Fig. 7.

The follower 58', in addition to the rollers 73 bearing against the upper flange of the support 28, has a roller 73' bearing against the rails 40.

A pin 91 on the hub of the crank 79 extends into a slot 92 formed in the forward face of the block 87. This limits the movement of the crank 79 so that if the overload-reverse causes the upper strand of the chain to move rearwardly the chain 77 will not be pushed up against the upper flange of support 28.

Intermediate the sprockets 75 and 76 is mounted an idler sprocket 93 which holds the sprocket chain 77 up away from the bottom of the channel-shaped support 28.

The electrically-controlled mechanically-operated clutch and brake mechanism 24 is shown in two forms, one for use with a unidirectional motor 26 (see Fig. 6) and the other for use with a reversible motor 26 (see Figs. 11, 12, and 13).

The clutch and brake mechanism 24, for use with the unidirectional motor, comprises a pair of driving clutch members 94 and 95 and a pair of driven clutch members 96 and 97. For the worm-type draft mechanism 22, both pairs of clutch members, together with a brake drum 98, are mounted on the tube 64. For the chain and

sprocket draft mechanism 23 the pairs of clutch members and brake drum 98 are mounted on the shaft 84. In either adaptation the clutch members and brake drum are operatively connected together by a lever and link mechanism 99, as will presently appear.

The driving clutch members 94 and 95 are rotatably mounted on the tube 64, or the shaft 84 (depending upon the type of draft mechanism), and have beveled gear teeth formed on their inner opposed faces which mesh with a beveled pinion 100 connected to the motor 26.

The driven clutch members 96 and 97 are slidably keyed to collars 101 and 102 which, in turn, are secured by set-screws 103 to rotate with the tube 64 or shaft 84, as the case may require. Friction rings 104 are secured to the faces of the driven clutch members 96 and 97 to engage the opposed faces of the driving clutch members 94 and 95, when the clutch members 96 and 97 are shifted axially toward said driving clutch members 94 and 95. Being secured to rotate with the tube 64 or shaft 84 the collars 101 and 102 hold the driving clutch members 94 and 95 against axial movement on said tube or shaft.

The brake drum 98 may be a separate unit from the clutch mechanisms, as shown in Figs. 6 and 8, and secured by a set-screw 105 to the tube 64 or shaft 84 to rotate in unison with the driven clutch members 96 and 97, or it may be formed integral with one of the driven clutch members, as shown in Figs. 11, 14, and 15. A friction-lined brake shoe 106 is mounted on a brake-shoe member 107 so as to be shifted into and out of engagement with the periphery of the brake drum 98.

The lever and link mechanism 99, which controls the shifting of the driven clutch members 96 and 97 and the brake-shoe supporting member 107, comprises a pair of levers 108 and 109 respectively connected to the driven clutch members 96 and 97 and which levers are in turn connected by links 110, 111, and 112 to a rocker arm 113 so as to relate the shifting of the brake shoe with the shifting of the clutch members 96 and 97. A spring 114 connects together levers 108 and 109 at their lower ends and, by reason of the connection of said levers to the brake shoe 106 and its engagement with the brake drum 98, normally holds the driven clutch members 96 and 97 out of engagement with the driving clutch members 94 and 95, when the electro-magnets 115 and 116, respectively connected to the levers 108 and 109, are de-energized.

The levers 108 and 109 are of the conventional Y-shaped form, such as appears from Fig. 7. At their upper ends they are pivotally supported on the housing 60 by means of pins 117. Inwardly of these pivots the levers are connected to the respective driven clutch members 96 and 97 by means of pins 118 on the conventional collars 119 (see Fig. 7).

The links 110 and 111 have their upper ends pivotally connected to the respective levers 108 and 109 and their lower ends are connected together with the end of the link 112, pivoted to the arm 113, so that any movement of either one of the levers 108 and 109 will actuate the brake-shoe supporting member 107, through the medium of the arm 113 pivoted at 120 on the housing 60. The link 112 is made adjustable, as shown at 121 (see Fig. 6), so that the shifting of the brake shoe supporting member 107 may be properly correlated with the shifting of either of the levers 108 or 109 under the influence of either

the spring 114 or the energized electro-magnets 115 or 116.

The electro-magnets 115 and 116 are secured to supports, mounted on the housing 60, on opposite sides of the levers 108 and 109 respectively. The armatures 122 and 123 are pivotally connected to the respective levers 108 and 109 by pins 124 and 125 set in elongated slots 126 and 127.

10 The clutch and brake mechanism 24 for use with a reversible motor and a spiral shaft (see Figs. 11, 12, and 13) comprises a driving clutch member 128 and a driven clutch member 129 which, together with a brake shoe drum 98 (integral with the driven clutch member 129), are mounted on the tube 64. The engaging and disengaging operations of the clutch members with each other and of the brake shoe with the brake drum are synchronized through the medium of a pair of co-acting levers 130 and 131, as will appear presently.

15 The driving clutch member 128 is free to rotate on the tube 64 and is axially shiftable thereon toward and away from the driven clutch member 129. It is connected by a belt 132 to a pulley on a reversible motor 26. A friction ring 133 is secured on the inner face of the driven clutch member 129 to engage the opposed face of the driving clutch member 128. A spring 134, interposed between a collar 135 and a roller bearing ring 136, normally urges the driving clutch member 128 against the driven clutch member 129. The collar 135 is threaded on the tube 64 so that it may be shifted axially of the tube to adjust the tension of the spring 134. A set-screw 137 holds the collar 135 against axial movement on the tube 64, once it has been set to secure the desired tension of the spring 134.

20 The driven clutch member 129 is secured to rotate with the tube 64 by means of bolts 138.

25 The brake drum 98, in this modification, is in the form of a flange integral on the driven clutch member 129 and is adapted to be engaged by the brake shoe 106 supported on the shiftable member 107. A spring 139, interposed between the brake shoe 106 and a piston cup 140 and slidably mounted in the member 107, is adapted to normally urge the brake shoe 106 into engagement with the brake drum 98.

30 The lever 130 is mounted to shift with or shift the driving clutch member 128, whereas the lever 131 is mounted to move with or move the brake-shoe supporting member 107. Movement of the lever 131 is adapted to effect movement of the lever 130 through the action of the co-acting cam surfaces 141 and 142.

35 The lever 130 is of the conventional Y-shaped form. At its upper end it is pivotally supported by a pin 143 to the housing 60 and is connected by pins 144 to a collar 145 of the conventional type on the driving clutch member 128. When the spring 134 is free to act this lever 130 moves with the driving clutch member 128. On the other hand, when the spring 139 is free to act, so as to elevate the outer end of the lever 131, the action of the cam roller 142 against the inclined cam surface 141 will cause the lever 130 to retract the clutch member 128, against the normal pressure of the spring 134.

40 The lever 131 is also of the conventional Y-shaped form. At its outer end it is pivotally supported on the housing 60 by means of a pin 146 and is connected to the brake shoe support 107 by pins 147. Adjacent to its outer end the lever 131 is connected to an armature 148 of the electro-

magnet 149 by means of a pin 150. The cam member 142, which is in the form of a roller, is mounted on the lever 131 intermediate the connection of said lever 131 to the brake shoe support 107 and the connection to the armature 148. 5

In this modification (Fig. 11) the brake shoe support 107 is slidably supported on a post 151, the stem 152 of which is adjustably secured to the housing 60 by means of a pair of nuts 153. The piston cup 140 rests against the forked upper end of post 151 and against an arm 154 of a bell-crank lever 155. The arm 156 of said bell-crank lever 155 is connected, by an adjustable link 157, to a rocker arm 158 pivotally supported on the housing 60 by means of a link 159. The rocker arm 158, in turn, is connected to the "overload" control mechanism, as will appear more fully hereinafter. The pin 146 and the pivot for the bell-crank lever 155 are on a plate 155a slidably supported on the housing 60 and shiftable by means of the adjusting nuts 155b.

The electrically-controlled magnetically-operated clutch and brake mechanism 25 is shown in two forms, one for use with a unidirectional motor 26 (see Fig. 14) and the other for use with a reversible motor 26 (see Fig. 15). The two forms of the magnetic clutch and brake mechanisms are respectively comparable to the two forms of the electrically-controlled mechanically-operated clutch and brake mechanisms hereinbefore described, except that magnetic means for shifting the clutch members are substituted for the link and lever mechanisms. However, both forms of the electrically-controlled magnetic ally-operated clutch and brake mechanism 25 are herein shown applied to the worm-type draft mechanism 22.

The clutch and brake mechanism 25, for use with the unidirectional motor (see Fig. 14), comprises a pair of driving clutch members 94' and 95' and a pair of driven clutch members 96' and 97'. Both pairs of clutch members, together with a brake drum 98', are mounted on the tube 64. The engagement and disengagement of such clutch members is controlled by the electro-magnets 160 and the engagement and disengagement of the brake shoe with the brake drum is controlled by the co-action of a spring 139 and an electro-magnet 149 such as shown in Fig. 11.

The driving clutch members 94' and 95' are rotatably mounted on the tube 64 and have beveled gear teeth formed on their opposed faces, which mesh with a beveled pinion 100', connected to the motor 26.

Each of these driving clutch members 94' and 95' mounts an armature ring 161 and 162 on spring discs 163 secured to the hubs of the members 94' and 95', outwardly of the gear faces. These spring discs permit an axial movement of the armature rings 161 and 162 toward and away from their respective co-acting driven clutch members 96' and 97' under the influence of the magnets 160.

The driven clutch members 96' and 97' are secured to rotate with the tube 64, by means of set-screws 164. Friction rings 104' are secured to collars 165 threadingly supported on the driven clutch members 96' and 97'. The collars 165 may be rotated so as to properly adjust the distance between the friction rings 104' and the armature rings 161. Once adjusted, they are held in place by means of set-screws 166.

Several of the electro-magnets 160 are set in the faces of the driven clutch members 96' and 97' with the cores positioned, so that when ener-

gized, they will attract the armature rings 161 and 162 and hold them in proper frictional engagement with the friction rings 104' on the driving clutch members 94' and 95'. The electro-magnets 160 are connected to a source of electricity through the medium of ring connectors 167 and 168 insulatingly mounted on the hubs of the respective driven clutch members 96' and 97'.

The brake drum 98' is integrally formed with the driven clutch member 97' and is adapted to have a brake shoe 106' shifted into and out of engagement therewith by means of a lever 131' under the co-action of the spring 139 and electro-magnet 149, as will more fully appear from a description of the modification shown in Fig. 15.

The modification of the electrically-controlled magnetically-operated clutch and brake mechanism 25 for use with a reversible motor, as is shown in Fig. 15, comprises a driving clutch member 128' and a driven clutch member 129', the engagement and disengagement of which are controlled by the electro-magnets 160.

The driving clutch member 128' is journaled to rotate on the tube 64 and is driven by a belt 132' connected to a motor 26, in a manner similar to that shown in Fig. 12. Friction rings 133' are mounted on the face opposed to the driven clutch member 129'.

The driven clutch member 129' is secured to rotate with the tube 64 by means of bolts 138'. An armature ring 161' is mounted on the member 129' by means of a spring disc 163', which permits the armature 161' to be drawn into frictional engagement with the friction rings 163' by the action of the electro-magnets 160.

The electro-magnets 160 are connected to a source of power by means of a pair of ring connectors 167', insulatingly supported on the hub of the driving clutch member 128'.

The brake drum 98' is secured directly to the driven clutch member 129', to rotate in unison therewith. It is adapted to have a brake shoe 106, supported on the shiftable member 107, moved into and out of engagement therewith by means of a lever 131' under the co-action of the spring 139 and the electro-magnet 149.

As explained in connection with the modification shown in Fig. 11, a spring 139 is interposed between the brake shoe 106 and a piston cup 140, slidably mounted in the member 101. The spring 139 is adapted to normally urge the brake shoe 106 into engagement with the brake drum 98', thereby shifting the lever 131 to the dotted position shown in Fig. 15, unless the force of the spring 139 is counteracted by the electro-magnet 149, the armature 148 of which is connected by a pin 150 to the lever 131'.

The lever 131' is of the conventional Y-shape, such as shown in Fig. 13. The ends thereof are pivotally supported on the housing 60 by means of a pin 146. Inwardly of said pivotal connection the lever 131' is connected to the brake shoe support 107 by means of pins 147.

The brake shoe mechanism in this modification (Fig. 15) has associated with it a bell-crank lever 155 which is connected by an adjustable link 157 to a rocker arm 158 which, in turn, is connected to the "overload" control mechanism, as has been previously described in connection with the modification shown in Fig. 11.

For either of the forms of draft means (the worm mechanism 22 or the chain-sprocket mechanism 23) an "overload" switch cut-out mechanism is provided, so that in case the door, in 75 being moved toward its closed position, strikes an

obstruction the electrical circuit to the motor and the clutch and brake mechanism is instantly cut off. The "overload" switch may be so constructed as to automatically reverse the operating mechanism and return the door to its fully open position.

The "overload" switch cut-out mechanism for the worm-type of draft mechanism 22 comprises a member 169 mounted on the spirally-threaded shaft 56 in position so that an axial shifting of the shaft 56 will cause the member 169 to shift a normally retracted switch-actuating member 170. The member 169 is secured to the shaft 56 intermediate the bearing 61 and the cap 67 for the tube 64. It is held in place by one or more collars 171, keyed to the shaft by a set-screw 172, which permit axial adjustment of the member 169 relative to the shaft 56 so as to properly time the contact of the shaft-shifted member 169 with the switch-actuating member 170.

The switch-actuating member 170 is shown in different forms in Figs. 6 and 11. In Fig. 6 a pin is normally urged by a spring 173 to shift the roller 174 into engagement with the cam surface 175 on the member 169. In Fig. 11 an arm is pivoted at 176 and urged by gravity and a spring-actuated "overload" switch, hereinafter referred to, to hold the roller 174 in contact with the cam surface 175 on the member 169. The "overload" switch would be located so as to be actuated by the other end of the pin or arm 170.

The "overload" switch cut-out mechanism, for the chain-and-sprocket type of draft mechanism 23, comprises a member 169' pivoted on the channel-shaped support 28 at 177, intermediate the reaches of the belt 82, so that rollers 178 and 179 contact the outside faces of the opposite reaches of said belt 82. A spring 180 normally urges the member 169' to keep the roller 179 in contact with the underside of the lower reach of the belt 82. The strength of this spring 180 is such that, as shown in Fig. 9, it holds the lower reach of the belt out of the straight position which it would normally occupy during the drive of the motor 26 to actuate the draft mechanism 23 to close the door. Therefore, if during the operation of the draft means 23 to close the door the door is obstructed, the temporary additional strain of the power applied to the lower reach of the belt 82 tends to move it toward the straight position shown in dotted outline in Fig. 9. This results in a movement of the member 169' against the action of the spring 180 which moves a switch-actuating member comparable to the switch-actuating member 170 shown in Figs. 6 and 11.

The general character of the switch-controlled electrical circuits, which determine the operation of the various modifications of clutch and brake mechanisms and consequently the opening and shutting of the door 20, is diagrammatically illustrated in Figs. 10 and 16. Fig. 10 diagrams the power and control circuits for clutch and brake mechanism 24, such as shown in Fig. 6 or 8. Fig. 16 diagrams the power and control circuits for a clutch and brake mechanism 25, such as shown in Fig. 14.

As will be apparent from the previous description of these forms of clutch and brake mechanisms 24 and 25, the diagrams of Figs. 10 and 16 are arranged for a unidirectional motor. In cases where the clutch and brake mechanisms 24 and 25 of the types shown in Figs. 11 and 15, employing a reversible motor, the electrical circuits would be the same as that shown in Fig. 16

except that the wiring to the motor 26 would have to be altered so as to reverse the flow of the current through the motor.

In these diagrams the power circuit is shown in heavy lines whereas the control circuit is shown in lighter lines. In these diagrams the motor and the electro-magnets, to which reference has been made heretofore, are numbered as they have been in the respective Figures 6 and 14.

In each case the flow of current to the motor and the several electro-magnets is controlled by the contactor switches 181 and 182, the action of which are controlled by the respective electro-magnets 183 and 184, connected in the control circuit. The control circuit is provided with an "up" switch 185, a "down" switch 186, a "stop" switch 187, an "overload-reverse" switch 188, a "limit" switch 189, and an "isolating" switch 190. Interlocking switches 191 and 192 are also arranged in the control circuit, the opening and closing of which is determined by the shifting of the armatures for the electro-magnets 183 and 184, respectively. The switches 185, 186, 187, and 188 are all double-pole single-throw spring-retarded push-button type. The switches 185 and 186 normally have one pole closed and the other open. Switch 187 has both poles normally closed. Switch 188 also has one pole closed and one pole open, but reversed in order as respects switches 185 and 186. Switches 189 and 190 are normally closed.

The operation of this improved door mechanism is as follows:

Regardless of which of the two poles of draft mechanism is used or which of the clutch and brake mechanism modifications is employed for connecting the motor to the draft means, it is obvious that the pull or the push of the draft mechanism is applied to the door through the draft means acting on the follower 58 or 58'. The pinions 34 meshing with the racks 41 ensure an equal movement of the rollers 35 and 37 at both sides of the door along the tracks 40.

Assuming the door 20 is in its closed position, as shown in Fig. 1, the unreeling of the cables 46 from the drums 42 has put the springs 49 under proper tension to counterbalance the door by reason of the winding of the springs 49. This tension helps to facilitate the opening of the door and lessens the power that would be required otherwise to start the door the instant the power of the motor 26 is applied, through the medium of the draft means 22 or 23. As the two pinion-roller combinations 34 move along the track and rack combinations 40 and 41 the casters 29 move along the tracks 30. When the door has reached its full open position, as shown in dotted outline in Fig. 1, the cable 46 has caused a slight rewinding of the spring 49 so that there is sufficient torque in the spring to give a boost to starting the door on its movement toward its closed position, when the power of the motor 26 is again applied for that purpose through the draft means 22 or 23.

Regardless of the type of draft means, or the modifications of the clutch and brake mechanisms that may be employed for shifting a door of this kind, the movement of the door is controlled by the switch mechanisms shown in the diagrammatic views of Figs. 10 and 16. When it is desired to elevate the door the "up" switch 185 is shifted. This closes the circuit to the electro-magnet 183 and causes a closing of the "interlocking" switch 191 and the "contactor" switch

181. Because of the character and arrangement of the other switches in the control circuit the "interlocking" switch 191 keeps the electro-magnet 183 energized until one of the switches 187, 188, or 189 is shifted.

The closing of the "contactor" switch 181 simultaneously energizes the electro-magnet 115 and the motor 26. The energization of the electro-magnet 115 causes a retraction of the armature 122 which shifts the lever 108 to further retract the clutch member 96 and through the action of the spring 114 shifts the lever 109 to bring the clutch member 97 into contact with the clutch member 95. The further shifting of the lever 108 by the electro-magnet 115, causes the links 110, 111, 112 to actuate the arm 113 to cause the retraction of the brake shoe 106 from the brake drum 98. Thereupon the motor 26 revolves the spiral threaded shaft 56 and causes the follower 58 to move along the shaft 56 to open the door 20.

If it were desired to check the movement of the door, prior to its reaching its full open position, a pushing of the "stop" switch 187 would break the circuit to the electro-magnet 183. Thereupon the armature thereof would be shifted to open the "contactor" switch 181, breaking the circuit to the electro-magnet 115 and to the motor. The spring 114 would thereupon restore the levers 108 and 109 to their normal positions, the movement of which would be communicated through the links 110, 111, 112, and the arm 113 so as to again synchronize the shifting of the brake shoe 106 into contact with the brake drum 98 with the retraction of the clutch member 97, thus causing an instantaneous checking of the rotation of the shaft 56.

If, on the other hand, the door were allowed to complete its movement to a full open position, upon reaching that position suitable means on the door would engage and hold open a "limit" switch 189 (see Fig. 1) adjacent the inner end of the channel-shaped support 28. The shifting of the "limit" switch would break the circuit to the electro-magnet 183 which would result in the clutch and brake operating mechanism 99 restoring the clutch and brake mechanism to the normal position shown in Fig. 6.

When it is desired to close the door, the "down" switch 186 would be pressed. This would cause an energization of the electro-magnet 184 resulting in a retraction of the armature therefor and thereby closing the "interlocking" switch 192 and the "contactor" switch 182. The results would be identical with what has previously been explained in connection with the switches 191 and 181. The energization of the electro-magnet 116 would cause the armature 123 to shift the lever 109 to further retract the clutch member 97 which movement would be communicated through the spring 114 to the lever 108 causing the engagement of the clutch member 96 with the clutch member 94. The link mechanism 110, 111, 112 acting on the arm 113 will cause a synchronized retraction of the brake shoe 106.

Unless the movement of the door toward its closed position is otherwise arrested, it will continue until it reaches its closed position. Thereupon a suitable member on the door will engage, and hold open, the "isolating" switch 190 at the opposite end of the channel-shaped support 28. The opening of the "isolating" switch 190 opens the circuit to the normally-open pole of the "overload" switch 188 so that when the door approaches its fully-closed position the draft mech-

anism is actuated, as hereinbefore explained, to shift the switch-actuating member 170 to open the circuit to the electro-magnets and the motor. Were it not for the opening of the "isolating" switch 190 the actuation of the "overload" switch 188 would cut in the circuit whereby the motor is caused to open the door, thus returning the door to its fully-open position, instead of checking its movement at its fully-closed position.

If, however, in the course of its movement toward a closed position the door 20 should strike an obstruction, the checking of the movement of the door would be transmitted to the shaft 56, causing an axial movement thereof against the spring 68. This would result in a movement of the member 169 whereupon the switch-actuating member 170 would be shifted to cause retraction of the "overload-reversing" switch 188. The shifting of this switch 188 would break the circuit to the electro-magnet 184, resulting in retraction of the "contactor" switch 182 and the "interlocking" switch 192, thereby causing restoration of the clutch and brake mechanism to its normal position as shown in Fig. 6.

However, the establishing of contact across the terminals in the dotted lines leading to the "isolating" switch 190 would result in an energization of the electro-magnet 183. This would cause its armature to close the "interlocking" switch 191 and the "contactor" switch 181, whereupon the electro-magnet 115 and motor 26 would be simultaneously energized to cause a movement of the door toward its open position, as previously explained.

Where the clutch and brake mechanism 25 is of the type shown in Fig. 14, the movement of the door would be exactly the same, under the control of the switch mechanisms which have just been described with regard to Fig. 10 for the modification shown in Fig. 6. The only difference would be that the closing of the "contactor" switch 181 or 182 would result in an energization of the electro-magnets 160 for either the clutch member 96' or 97', causing an attraction of either the armature 161 or the armature 162 and thereby effecting the engagement of the respective driving and driven clutch members. Simultaneously with the energization or de-energization of the electro-magnets 160, for either of the clutch members 96' or 97', the electro-magnet 149 would be energized or de-energized to effect the operation of the brake mechanism shown in Fig. 15.

If either of the clutch and brake mechanism modifications shown in Figs. 11 or 15 were employed, the door mechanism would have the same movements as already explained under the influence of the same switch mechanisms.

Where the modification shown in Fig. 11 is employed the energization of the electro-magnet 149 would cause the armature 148 to shift the lever 131 into the full-line position shown in Fig. 11. This would permit the spring 134 to shift the driving clutch member 128 into contact with the driven clutch member 129 which would locate the lever 130 in the full-line position shown in Fig. 11. Upon the opening of the control circuit to de-energize the electro-magnet 149 the spring 139 would cause a shifting of the lever 131 into the position shown in dotted outline whereupon the roller cam 142, engaging the cam surface 141 on the lever 130, would retract the driving clutch member 128 from contact with the driven clutch member 129.

Where the modification, shown in Fig. 11, is

used in connection with the spiral screw type draft means 22, and the door were to meet an obstruction as it moved toward its closed position, the axial shifting of the shaft 56 not only would cause the member 169 to shift the switch-actuating member 170, to operate the "overload" switch 188, but the movement of the member 169 would be transmitted through the arm 158, link 157, and bell-crank lever 156 to increase the tension on the spring 139. This would not only ensure the disengagement of the driving clutch member 128 but also cause an increased pressure of the spring 139 to urge the brake shoe 106 against the drum 98.

Where the modified form of clutch mechanism shown in Fig. 15 is employed, the engagement and disengagement of the driving clutch member 128', with the driven clutch member 129', is controlled directly, whereas the retraction or application of the brake shoe 106 is controlled by the de-energization or energization of the electromagnet 149. The shifting of the bell-crank lever 155, when the shaft 56 has been given an axial movement against the action of the spring 68 due to the door meeting an obstruction as it moved toward its closed position, also would be effected as hereinbefore set forth.

When either of the clutch or brake mechanism modifications shown in Figs. 6 and 14 is employed, in connection with the chain and sprocket means 23, the operation under the action of the switch mechanisms shown in Figs. 10 and 16 is the same as hereinbefore described, except that, when the door meets an obstruction, as it moves toward its closed position, the normal tension on the belt 82 is reversed from the situation shown in full outlines in Fig. 9 so that the arm 169' is shifted against the action of the spring 180 thereby causing a movement of the switch-actuating member 170'.

Other variations and modifications in the details of structure and arrangement of the parts may be resorted to within the spirit and coverage of the appended claims.

I claim:

1. The combination with a door shiftable between a vertically-disposed closed position and an overhead open position, of overhead horizontal tracks, brackets attached to said door and supporting rollers for travel on said tracks, a motor, a shaft extending parallel to said tracks and having a spiral thread formed thereon approximately the length of said tracks, said shaft being axially shiftable in its bearings, resilient means normally urging said shaft toward one extreme axial position, a follower block connected to said door and formed to mesh with the thread on said shaft so as to traverse said shaft when it is rotated and thereby shift said door between its closed and open positions, a driven clutch member and a brake shoe drum connected to rotate with said shaft, a co-axially mounted co-acting driving clutch member connected to said motor, said clutch members being axially shiftable relative to each other into and out of driving engagement, a brake shoe, a second resilient means normally urging said brake shoe into engagement with said brake drum, a third resilient means normally urging the axially-shiftable clutch member into engagement with the other said clutch member, a lever for shifting said shiftable clutch member against the action of said third resilient means, a second lever connected to said brake shoe, co-acting cam elements on said levers arranged so that said clutch lever is retracted when

said brake-shoe lever is actuated by said brake-shoe resilient means, electro-magnetic means connected to retract said brake-shoe lever when said means is energized, an electrical circuit connecting said electro-magnetic means and said motor with a source of power, means on said shaft adapted to actuate a circuit breaker for said circuit when said shaft is shifted axially against the action of said first-mentioned resilient means, a bell-crank lever having one arm thereof positioned to press against the end of said brake-shoe resilient means, and a link mechanism connecting the other arm of said bell-crank lever to said circuit-breaker actuating means whereby the axial shifting of said shaft increases the compression of said brake-shoe resilient means.

2. The combination with a door shiftable between a vertically-disposed closed position and an overhead open position, of overhead horizontal tracks, a shaft extending parallel to said tracks and having a spiral thread formed thereon approximately the length of said tracks, a follower block connected to said door and formed to mesh with the thread on said shaft so as to traverse said shaft when it is rotated and thereby shift said door between its open and closed positions, a housing mounted at the end of one of said tracks and providing a bearing for said shaft, a sleeve keyed to said shaft, a tube concentrically arranged with said shaft and journaled on said housing and having telescopic engagement with said sleeve, means connecting said tube rotatively with said shaft but permitting relative axial movement of said shaft and tube, a cap on the end of said tube, a spring interposed between said cap and said sleeve end to normally urge said shaft toward one extreme axial position, a driving clutch member rotatably mounted on said tube and connected to said motor, a driven clutch member keyed to said tube, said clutch members being axially shiftable relative to each other into and out of cooperative engagement, means for causing the relative shifting of said clutch members, a spring normally urging said clutch-shifting means in one direction, electro-magnetic means connected to actuate said clutch-shifting means in the opposite direction, and a switch-controlled circuit connecting said electro-magnetic means and said motor with a source of power.

3. The combination with a door, of means for guiding the door in movement through a predetermined path, a rotatable shaft, means connecting said shaft with said door whereby rotation of said shaft will effect movement of said door, a brake normally applied to said shaft for securing said shaft against rotation, an electric circuit, a motor in said circuit, a normally disengaged clutch including a driving clutch member connected to said motor and a driven clutch member coaxial with said driving clutch member and connected to said shaft, one of said clutch members being axially shiftable into and out of engagement with the other clutch member, coacting levers connecting the axially shiftable clutch member and said brake whereby said clutch may be engaged and disengaged when said brake is respectively disengaged and engaged, and electromagnetic means in said circuit connected to actuate said levers to disengage said brake and engage said clutch when said circuit is closed.

4. The combination with a door, of means for guiding the door in movement through a predetermined path, a rotatable shaft, means connecting said shaft with said door whereby rota-

tion of said shaft will effect movement of said door, a brake normally applied to said shaft for securing said shaft against rotation, an electric circuit, a motor in said circuit, a bevel pinion connected to said motor, a pair of coaxial driving clutch members having bevel gears formed on their opposed faces meshing with said pinion, a pair of driven clutch members connected to said shaft and coaxial with said driving clutch members and shiftable axially into and out of engagement therewith, a pair of levers connected to said driven clutch members, resilient means connected to said levers to normally disengage said clutch members, links connecting said clutch levers with said brake to effect the disengagement and engagement of said brake with said shaft when said clutch members are respectively engaged and disengaged, and electromagnetic means in said circuit and connected to said levers to selectively engage one of said driven clutch members with one of said driving clutch members against the action of said resilient means.

5. The combination with a door, of means for guiding the door in movement through a predetermined path, a rotatable shaft, means connecting said shaft with said door whereby rotation of said shaft will effect movement of said door, a brake normally applied to said shaft for securing said shaft against rotation, an electric circuit, a motor in said circuit, a bevel pinion connected to said motor, a pair of coaxial driving clutch members having bevel gears formed on their opposed faces meshing with said pinion, a pair of driven clutch members coaxial with said driving clutch members and connected to said shaft, said driving clutch members being axially shiftable into and out of engagement with said driven clutch members, resilient means normally urging said clutch members out of engagement, electromagnetic means connected in said circuit and carried by said driven members for selectively engaging said clutch members, and other electromagnetic means in said circuit for disengaging said brake.

6. The combination with a door, of means for guiding the door in movement through a predetermined path, a rotatable shaft, means connect-

ing said shaft with said door whereby rotation of said shaft will effect movement of said door, an electric circuit, a motor in said circuit, a driven clutch member connected to said shaft, a driving clutch member connected to said motor and shiftable into and out of engagement with said driven member, a lever for shifting said driving member, resilient means normally urging said driving member toward engagement with said driven member, a brake drum connected to said shaft, a brake shoe movable into and out of engagement with said drum, a lever for moving said shoe, second resilient means urging said shoe into engagement with said drum, electromagnetic means in said circuit and connected to said brake lever for disengaging said brake shoe and said drum, and coacting cam elements on said levers arranged to synchronize the engagement and disengagement of said clutch members respectively with the disengagement and engagement of said brake shoe and brake drum.

Certificate of Correction

Patent No. 2,568,808

September 25, 1951

KARL E. JOHANSON

It is hereby certified that error appears in the printed specification of the above numbered patent requiring correction as follows:

Column 3, line 30, after "drum" insert *42*; column 7, line 34, after "magnetic" insert a hyphen; column 10, line 35, for "poles" read *types*; column 12, line 42, for "wold" read *would*;

and that the said Letters Patent should be read as corrected above, so that the same may conform to the record of the case in the Patent Office.

Signed and sealed this 22nd day of January, A. D. 1952.

[SEAL]

THOMAS F. MURPHY,
Assistant Commissioner of Patents.
